US00D659748S

(12) **United States Design Patent**
Helgesson et al.

(10) **Patent No.:** **US D659,748 S**
(45) **Date of Patent:** **** May 15, 2012**

(54) **PAYMENT TERMINAL FOR A FUEL
DISPENSER**

(75) Inventors: **Hanna Helgesson**, Malmo (SE); **Annika Birkler**, Malmo (SE); **Bengt I. Larsson**, Skivarp (SE); **Carl Forslund**, Hollviken (SE); **Camilla Lundstrom**, Angelholm (SE); **Scott R. Negley, III**, Austin, TX (US); **Neil Thomas**, Austin, TX (US); **Kevin Burnett**, Round Rock, TX (US); **Gian Pangaro**, St. Somerville, MA (US); **Gen Suzuki**, Cambridge, MA (US); **Jason Robinson**, Tewksbury, MA (US); **Timothy Raymond Proulx**, Nashua, NH (US)

(73) Assignee: **Dresser Wayne AB**, Malmo (SE)

(**) Term: **14 Years**

(21) Appl. No.: **29/359,677**

(22) Filed: **Apr. 14, 2010**

(57) **CLAIM**

The ornamental design for a payment terminal for a fuel dispenser, substantially as shown and described.

DESCRIPTION

FIG. 1 is a perspective view from above illustrating the front and left side of a first embodiment of a payment terminal for a fuel dispenser;

FIG. 2 is a front view thereof;

FIG. 3 is a right side view thereof;

FIG. 4 is a rear view thereof;

FIG. 5 is a left side view thereof;

FIG. 6 is a top view thereof;

FIG. 7 is a perspective view from above illustrating the front and left side of a second embodiment of a payment terminal for a fuel dispenser;

FIG. 8 is a front view thereof;

FIG. 9 is a right side view thereof;

FIG. 10 is a rear view thereof;

FIG. 11 is a left side view thereof; and,

FIG. 12 is a top view thereof.

The bottom of the payment terminal for a fuel dispenser is not part of the claimed design.

1 Claim, 12 Drawing Sheets
